(57) **CLAIM**

We claim the ornamental design for a drain cover, as shown and described.

DESCRIPTION

FIG. 1 is a top perspective view of a first embodiment of a drain cover of the present invention;

FIG. 2 is a top view thereof;

FIG. 3 is a bottom view thereof; and

FIG. 4 is a first side view thereof, wherein the second, third, and fourth side views are mirror images thereof;

FIG. 5 is a top perspective view of a second embodiment of a drain cover of the present invention;

FIG. 6 is a top view thereof;

FIG. 7 is a bottom view thereof; and

FIG. 8 is a first side view thereof, wherein the second, third, and fourth side views are mirror images thereof

FIG. 9 is a top perspective view of a third embodiment of a drain cover of the present invention;

FIG. 10 is a top view thereof;

FIG. 11 is a bottom view thereof; and,

FIG. 12 is a first side view thereof, wherein the second, third, and fourth side views are mirror images thereof.
